LOCOMOTIVE FIRE BOX.

1,402,182.

Specification of Letters Patent.

Patented Jan. 3, 1922.

Application filed November 12, 1917. Serial No. 301,631.

To all whom it may concern:

Be it known that I, JAMES T. ANTHONY, a citizen of the United States, residing at East Orange, in the county of Essex and State of New Jersey, have invented certain new and useful Improvements in Locomotive Fire Boxes, of which the following is a specification.

This invention relates to locomotive fire boxes, and the nature of the improvement and the objects and advantages of the invention will be best understood by a brief statement of certain of the difficulties encountered in connection with standard types of fire boxes at present in use.

Such fire boxes are of the square corner design, i. e., rectangular in shape, and the rear corners are extremely difficult to fire into, particularly in a wide type of fire box; and as a rule such corners either become filled with dead clinker and ash or are left vacant for the inrush of a blast of cold air, in either event the general efficiency of the fire box being lowered.

The large size of modern locomotives necessitates a corresponding increase in the fire boxes to secure sufficient grate area, as a result of which the cab space has been reduced to such an extent that most of the cabs are very crowded and cramped and hamper the engine crews.

In general, by my invention, I propose to provide a fire box having rounded corners for the purpose of preventing the formation of dead ash pockets and making it much more simple to keep the fire in the rear portion of the fire box. At the same time such a construction will provide the maximum effective grate area necessary to the large size locomotives, without cutting down the cab space, for the provision of the round cornered mud ring and fire box will eliminate the projecting corners and provide considerably greater space on the floor and deck of the cab.

In addition in the modern types of fire boxes, the rectangular or square cornered type of mud ring is stiff and inflexible and causes buckling and cracking of the side sheets and broken staybolts. The provision of a rounded corner mud ring will tend to eliminate much of such stiffness and inflexibility, and the rounding of the corners of the fire box walls will still further in-

crease the flexibility of the fire box, cutting down the liability of breakage, buckling, etc.

My invention also contemplates an arrangement of a round cornered fire box having the advantages above noted but which does not cut down the effective space in which the gases are mixed and consumed nor reduce the area of the crown sheet; and finally, the invention resides in the provision of a fire box having all of the advantages pointed out but which offers no difficulties in the method of construction and in maintenance and cleaning.

I accomplish the foregoing by means of a construction which I have illustrated in preferred form in the accompanying drawings, wherein—

Figure 1 is a longitudinal section through a fire box embodying my improvements; Figure 2 is a transverse section of half the fire box taken on the line II—II of Figure 1; Figure 3 is a similar section taken on the line III—III of Figure 1; and Figure 4 is a section taken on the line IV—IV of Figure 1.

In carrying out my invention I provide the usual form of outside fire box comprising the throat sheet 7, back head 8 and outside fire sheet or wrapper 9; and an inside fire box comprising the inside throat sheet 10, flue sheet 11, crown sheet 12 and side sheets 13, and back sheet 14. The circulation tubes 15 connect the front and rear water legs and carry any preferred form of brick arch or baffle 16. The water legs are closed by the mud ring 17.

It will be noted that the corners of the mud ring 17 are rounded and also that the corners of the inside and outside fire boxes are likewise rounded. The rounded corner effect of the fire boxes, however, is stopped short of both the crown sheet and of the top of the outer or wrapper sheet. Thus the rounded corners of the inside throat sheet are carried slightly above the throat sheet proper and merge into the lower portion of the flue sheet proper; and the rounded corners of the back sheet and the back head are carried approximately to the plane of the rear ends of the tubes 15. The rounding of the corners of the mud ring and the lower edges of the sheets is done with radii of substantial dimensions as clearly shown

in the drawing, but the rounding of the upper corners of the box is done with comparatively very small radii.

As hereinbefore pointed out this arrangement cuts off the corners of the fire box eliminating the formation of dead spaces; makes it easy to keep the fire in the rear of the fire box thus reducing the liability of the presence of open spaces permitting inrush of cold air; and increases the space available for the cab, while at the same time, the effective area of the grate is not reduced. It will also be observed that the full area of the crown sheet is maintained and that the effective space for the mixture and combustion of the gases is not cut down. In addition the whole structure has greater flexibility than the standard types, because of the round-cornered mud ring and the round corners of the fire box walls. If a larger radius is desired for the rear corners of the box, complicated flanges can be avoided by increasing the pitch of the slope on the back head. No difficulties therefore are encountered in connection with the method of construction and with maintenance and cleaning.

It will be seen that the arrangement forms at the corners a structure which constitutes substantially a frustum of a cone, the frustum terminating short of the crown sheet so as not to encroach on its evaporating surface.

I claim:

1. In a locomotive fire box structure having a mud ring and evaporating surfaces comprising a crown sheet and front, rear and side sheets the combination of materially rounded corners, the radii of the lower portions of which are of substantial dimensions whereby to eliminate dead

spaces in the fire bed and the radii of the upper portions of which are of comparatively small dimensions whereby to retain substantially the full effective evaporating 45 surface of the crown sheet.

2. A locomotive fire box structure having a crown sheet, and throat, rear and side sheets, said throat, rear and side sheets meeting and merging at the corners in curved 50 or rounded planes, the radii of the lower portions of which are of substantial dimensions whereby to eliminate dead spaces in the fire bed and the radii of the upper portions of which are of comparatively 55 small dimensions whereby to retain substantially the full effective evaporating surface of the crown sheet.

3. A locomotive fire box structure having a crown sheet and rear and side sheets, said 60 rear and side sheets meeting and merging in curved or rounded planes constituting rounded corners, the radii of the lower portions of which are of substantial dimensions whereby to eliminate dead spaces 65 in the fire bed and the radii of the upper portions of which are of comparatively small dimensions whereby to retain substantially the full effective evaporating 70 surface of the crown sheet.

4. A locomotive fire box structure having materially rounded corners, the radii of the lower portions of which are of substantial dimensions whereby to eliminate dead spaces in the fire bed and the radii of the 75 upper portions of which are of comparatively small dimensions whereby to retain substantially the full effective evaporating surface of the crown sheet of the box.

In testimony whereof I have hereunto 80 signed my name.

JAMES T. ANTHONY.
